INVENTOR:

Frederick L. McGahan,

BY *Hugh Wagner*,
ATTORNEY.

UNITED STATES PATENT OFFICE.

FREDERICK L. McGAHAN, OF LOS ANGELES, CALIFORNIA; VIOLA K. WALKER, ADMINISTRATRIX OF SAID FREDERICK L. McGAHAN, DECEASED, ASSIGNOR TO THE PURPOSED MIND DEVELOPMENT SECURITY ASSOCIATION OF THE WORLD, A TRUST COMPANY.

FIRE BOX.

1,423,346.

Specification of Letters Patent. Patented July 18, 1922.

Original application filed January 3, 1918, Serial No. 210,146. Patent No. 1,292,399. Divided and this application filed January 17, 1919. Serial No. 271,715.

To all whom it may concern:

Be it known that I, FREDERICK L. McGAHAN, a citizen of the United States, residing at the city of Los Angeles, in the county of Los Angeles and State of California, have invented certain new and useful Improvements in Fire Boxes, of which the following is a specification.

This application is a division from the 10 application of the same inventor for patent for locomotive filed January 3, 1918, Serial 210,146, which became Patent 1,292,399, Jan. 21, 1919, and relates more particularly to the fire-box of the locomotive, which fire-box is provided with a nozzle or a plurality of nozzles for feed thereinto of powdered fuel.

In the accompanying drawings forming part of this specification, in which like numbers of reference denote like parts wherever they occur,

Fig. 1 is a sectional view on the line 1—1 of Fig. 2 and shows part of the engine cab in elevation and the fire-box in section.

Fig. 2 is a side elevation of an engine cab partly broken away and shows the fire-box and fuel inlets in section.

The fire-box 1 is located in the usual relation to the cab 2 and fuel, preferably pul- 30 verized, is normally fed to the fire-box 1 through the inlets 6.

The fuel is forced by any suitable means, such as shown by my prior Patent 1,292,399, through the flexible joint 4 and pipes 5, 35 communicating with pipes 6, and is sucked through nozzles 7 by any suitable suction means or by the natural draft through the fire-box.

The fire-box is provided with the usual 40 grate-bars 8 upon which rests a longitudinal arch 9 which is located opposite the openings or nozzles 7, the object being that the powdered fuel is drawn into the fire-box 1 against the arch 9 and is diverted and di- 45 rected upwardly from the point of entrance into the fire-box to the upper part thereof. The arch 9 is elongated and approximately half egg-shaped in cross section as shown and thus directs the fuel as just described

and the upward forcing of the fuel is ac- 50 centuated by the heated air in the lower part of the fire-box 1, which heated air, rising, carries the powdered fuel with it. It will thus be seen that the fuel may be continuously fed into the fire-box, which is prefer- 55 able to the interrupted or spasmodic firing by firemen, as it results in greater certainty and regularity of fuel supply which is nec- 60 essary for a regular and reliable head of steam.

Another advantage of this mode of firing resides in the heating of the particles of powdered fuel in the upper part of the fire- 65 box 1 before the same settle upon the grate-bars 8, while in addition, the fuel is being simultaneously consumed in all parts of the fire-box instead merely in bank of coals upon the grate-bars 8. Thus quicker and more certain and more complete combustion is obtained.

The arch 9 is provided with the ridge 11 which assists the arch in directing the fuel upwardly in the fire-box 1. The top of the ridge is below the fire tubes 10 which extend from the tube sheet 12, as shown by Fig. 70 2 of the drawings. It will thus be seen that the tube sheet 12 forms one end wall of the fire-box. The fuel enters through the inlets 6, is diverted and directed by the arch 9 to the upper part of the fire-box from 75 which the products of combustion are drawn into and through the fire-tubes 10 in the well known manner.

Having thus described this invention, I hereby reserve the benefit of all changes in 85 form, arrangement, order, or use of parts, as it is evident that many minor changes may be made therein without departing from the spirit of this invention or the scope of the following claim.

I claim:

A fire-box for locomotives comprising a casing having end and side walls and grate bars forming the bottom of the fire-box, in combination with a tube sheet forming one 95 end wall of the fire-box, horizontal fire tubes extending from said tube sheet, an elongated deflector having upwardly-converging side

walls in the fire-box and positioned above the grate bars, the top surface of said deflector being below the said fire tubes, fuel discharge nozzles extending through opposite sides of the fire box and below the top of said deflector for delivering the charge of powdered fuel against the sides of said

deflector, and means for creating a draft through the fire box whereby the products of combustion are drawn from the fire-box 10 and through the fire tubes.

In testimony whereof I hereunto affix my signature.

FREDERICK L. McGAHAN.
